T. P. HOW.
RAILROAD CAR.

No. 7,969.

Patented Mar. 11, 1851.

Fig. 1.

Fig. 2.

UNITED STATES PATENT OFFICE.

THOS. P. HOW, OF BUFFALO, NEW YORK.

CONNECTING TRUCKS WITH CAR-BODIES.

Specification of Letters Patent No. 7,969, dated March 11, 1851.

To all whom it may concern:

Be it known that I, THOMAS P. How, of Buffalo, in the county of Erie and State of New York, have invented a new and Improved Mode of Connecting the Bodies of Railroad-Cars to the Trucks; and I do hereby declare that the following is a full and exact description thereof, reference being had to the accompanying drawings and to the letters of reference marked thereon.

The bodies of cars are at present generally attached to the trucks by a center pin or king bolt which is located in the center of the trucks, in which case all the tendency which they have to arrange themselves in conformity to the line of motion is produced by the resistance of the rails to the flanges of the wheels, and if by any means the flanges are raised above the rails, or the cars are thrown from the track, the trucks are left free to arrange themselves in any direction that obstructions or other circumstances may induce. The cars are also liable to a lateral motion while running, consequent upon the frequent changes in direction made by the trucks. They also have a tendency to press laterally against the outside rail in curves, thereby wearing the flanges of the wheels and loosening the rails, as well as rendering the cars liable to run off the track.

My invention consists in obviating the above named difficulties and giving the trucks a tendency to arrange themselves in the direction of the propelling power by the means hereinafter described.

Figure 1 is a side elevation of a car constructed upon my improved plan. Fig. 2 is a plan of the trucks with sections of the bolts by which the trucks are connected to the body of the car.

A is the body of the car.

B, B, are the trucks which are made in most parts like many of those in common use.

C, is a plank which is bolted or otherwise firmly attached to the cross timbers of each truck.

D, D, are pieces of cast iron which are fastened to each end of the plank C. Holes of the form represented in the drawings are cast in the plates D, D.

E, E, and N, N, are bolts or pins which are fixed in the body of the car, and which draw the trucks.

F, F, are cast iron cups which are made flat on the bottom with a flange around the

outside to keep the balls o, o, from rolling out. These cups are fastened to the frame of the truck.

H, H, are cups similar to the cups F, F, and are fastened to the body of the car in an inverted position over the cups F, F.

I, I, are india rubber springs which may be used or omitted.

o, o, are balls which support the weight of the car being placed in the cups F, F, with the cups H, H, resting on them. These balls should be made of iron or steel, and as nearly spherical as possible so as to roll with ease and regularity.

The operation is as follows: When the car is drawn forward by pulling upon the buffer L, the bolts or pins E, E, are drawn forward into notches in the plates D, D, leaving the bolts N, N, in a proper position to play freely in the holes at the rear end of the trucks. If motion is communicated to the car by pulling upon the buffer M, the body of the car is drawn in an opposite direction on the trucks, and the bolts or pins N, N, are drawn into notches which keep them from moving laterally, while the bolts E, E, are drawn out of the notches and are left free.

It will be obvious from the above description that in whichever direction the car may be drawn, the point of draft is always forward of the center of the trucks and consequently that they have a tendency, independent of the guidance of the rails, to follow the drawing power, and hence that they will be less liable to be thrown from the track by obstructions, or if thrown off the track will be less liable to run so far from it as to produce any serious result; also in turning upon curves the drawing power pulling inwardly will have a tendency to keep the flanges of the wheels from pressing against the outer rail of the track.

What I claim as my invention and desire to secure by Letters Patent is—

Connecting the bodies of cars to the trucks by two bolts to each truck working in the holes or mortises above described and represented, the whole being constructed and operating substantially as herein set forth.

THOMAS P. HOW.
